UNITED STATES PATENT OFFICE.

JOHN W. KENYON, OF NEW YORK, N. Y., ASSIGNOR TO GEORGE H. CLARKE,
OF MONTCLAIR, NEW JERSEY.

LOW-WATER ALARM.

SPECIFICATION forming part of Letters Patent No. 318,913, dated May 26, 1885.

Application filed March 28, 1885. (No model.)

To all whom it may concern:

Be it known that I, JOHN W. KENYON, a subject of the Queen of Great Britain, residing at New York, county and State of New York, have invented certain new and useful Improvements in Low-Water Alarms, of which the following is a specification.

The United States Letters Patent No. 176,318, granted to me on April 18, 1876, for improvements in low-water-alarm apparatus for steam-generators, are for an invention embracing the application of a light vessel adapted to retain water, to be used as a dead-weight to open the valve of a whistle when the water in the generator or boiler falls to the low level, said water-retaining vessel being located above the boiler in a chamber which is provided with a dip-pipe, whose lower end is in line with the water-level which it is desired to indicate by sounding an alarm, said chamber being full of water, in which the vessel is submerged, when the water in the boiler is above the lower end of the dip-pipe. A testing-pipe, provided with a stop-cock, is secured between the top of the boiler and the upper part of the chamber, so as to afford a means for putting the chamber in equilibrium with the steam-space of the boiler, thus causing the water contained in the chamber to fall back into the boiler through the dip-pipe, and leaving the retaining-vessel attached to the valve full of water, when it is required to ascertain the condition of the apparatus, which it is desirable to do once in a while, to insure that the same is in proper working order.

Now, this invention has for its object to simplify the construction and lessen the cost of manufacture of this class of low-water alarms, and to avoid the trouble and expense of fitting the testing-pipe, and drilling and tapping the extra hole in the boiler for its lower end. This I accomplish by casting or forming a channel or passage-way in the wall of the chamber, one end of which opens in the upper part of the interior of the chamber, and the other end opens directly into the steam-space of the boiler, by being located at the bottom of the stem or neck of the chamber, by which it is secured to the boiler. A plug or stop-cock is fitted into the wall of the chamber, so that this test-passage

may be opened or closed at pleasure; but to describe my invention more particularly, I will now refer to the accompanying drawings, in which—

Figure 1 is a vertical central section of my improvements in low-water alarms, showing the same applied to a boiler, and Fig. 2 is an underneath view of the same detached from the boiler.

The general arrangement of the chamber *a*, cover *b*, water-retaining vessel *o*, dip-pipe *f*, rod *l*, with valve formed thereon to close the passage *m* to the whistle, and whistle *k*; as shown in the before-mentioned Letters Patent No. 176,318, is adhered to in this invention; but the special construction of a whistle described and claimed in another application, filed as Case B, is here shown, in which the supporting-spring *h* is placed above the whistle instead of beneath the vessel *o*.

To provide a means of communication between the steam-space of the boiler and the chamber *a*, when the water in the boiler is above the end of the dip-pipe *f*, a channel or passage, *a'*, is formed in the wall of the chamber in any suitable manner, but preferably by coring it out when the vessel is cast. This passage *a'* has an outlet, *a''*, in the interior of the chamber above the vessel *o*, which outlet is closed by means of the screw-plug *j* projecting through the cap-piece and bearing *j'*, fitted in the side of the chamber; and the lower end, *a'''*, of the passage opens into the steam-space of the boiler at the bottom of the stem or neck *a'*, which is screw-threaded on its outer side, and fits into a hole tapped in the top of the boiler. By this construction it will be seen that the apparatus is much simplified, costs less to manufacture, is less liable to get out of order by reason of the reduction in the number of connections and joints, and is more easily applied to boilers, requiring one hole only to be made through the top of the same.

The function of the passage-way *a'* and screw-plug *j* will be readily understood, for when the screw-plug is closed and the level of the water in the boiler is above the bottom of the dip-pipe *f*, the chamber *a* and vessel *o* are full of water. The spring *h* with the pressure of the steam then holds the valve on the rod firmly

to its seat. Now, upon opening the screw-plug *j* the steam rushes up the passage-way *a'* into the chamber *a*, and displaces the water therein, and the water retained in the vessel *o* is sufficiently heavy to overcome the tension of the spring *h* and the steam-pressure against the valve, thus allowing the steam to escape through the whistle *k*, which escape, under these conditions, indicates that the apparatus is in proper working order. When the screw-plug *j* is closed, the pressure of the steam in the boiler forces the water up the dip-pipe *f* into the chamber *a*, which water, surrounding the vessel *o*, counteracts the weight of the water therein, and so allows the valve on the rod *l* to be closed by the resilience of the spring *h* and the steam-pressure.

Having now described my invention, what I claim, and desire to secure by Letters Patent, is—

1. In a low-water alarm, a water-chamber

secured on the top of the boiler, provided with a dip-pipe extending down to the water, and a channel or passage-way formed in its side or wall, and connecting the steam-space of the boiler with the upper part of the water-chamber, in combination with a stop-cock or screw-plug fitted in said chamber, so as to close said passage-way, substantially as and for the purpose set forth.

2. In a low-water alarm, in combination, the water-chamber *a*, having the channel or passage-way *a'*, formed in its side or wall, the screw-plug *j*, the dip-pipe *f*, the vessel *o*, rod *l*, and steam-whistle *k*, substantially as set forth.

In testimony whereof I have hereunto set my hand, at New York, county and State of New York, this 26th day of March, 1885.

JOHN W. KENYON.
